United States Patent

Des. 237,047
Patented Oct. 7, 1975

237,047

BOTTLE OR THE LIKE

James L. Westrich, Algoma, Wis., assignor to Algoma
Net Company, Milwaukee, Wis.

Filed May 24, 1973, Ser. No. 363,761

Term of patent 14 years

Int. Cl. D9—01

U.S. Cl. D9—63

Fig. 1

Fig. 2

Fig. 3

Fig. 4

FIG. 1 is a perspective view of a bottle or the like, showing my new design;

FIG. 2 is an end elevational view with the carrying strap being broken away for illustrative purposes;

FIG. 3 is a perspective view with the carrying strap being broken away for illustrative purposes showing the side opposite that seen in FIG. 1; and

FIG. 4 is a side elevational view.

I claim:

The ornamental design for a bottle or the like, as shown.
